Primary Examiner — Rhea Shields(74) *Attorney, Agent, or Firm* — Merchant & Gould P.C.**CLAIM**

The ornamental design for an electrosurgery console, as shown and described.

DESCRIPTION

FIG. 1 is a perspective view from the front/right of an electrosurgery console;

FIG. 2 is a front view of the electrosurgery console;

FIG. 3 is a rear view of the electrosurgery console;

FIG. 4 is a left side view of the electrosurgery console;

FIG. 5 is a right side view of the electrosurgery console;

FIG. 6 is a top view of the electrosurgery console; and,

FIG. 7 is a bottom view of the electrosurgery console.

The broken lines represent portions of the electrosurgery console that form no part of the claimed design.
